(57) **CLAIM**

The ornamental design for pair of jumping rope grippers, as shown and described.

DESCRIPTION

FIG. 1 is a front perspective view of the pair of jumping rope grippers of the instant invention wherein the left side is shown separated from the right side.

FIG. 2 is a rear perspective view thereof.

FIG. 3 is a left side view thereof.

FIG. 4 is a right side view thereof.

FIG. 5 is a front view thereof.

FIG. 6 is a rear view thereof.

FIG. 7 is a top view thereof.

FIG. 8 is a bottom view thereof.

FIG. 9 is a front perspective view thereof.

FIG. 10 is a side view thereof.

FIG. 11 is a front perspective view without the spring thereof.

FIG. 12 is the same as FIG. 10 but shown without the spring; and,

FIG. 13 is a side view with the jumping rope connected thereof.

The broken lines depict portions of the structure that form no part of the claimed design.
